UNITED STATES PATENT OFFICE.

RENÉ BABLON, OF LES LILAS, FRANCE.

CONSTRUCTION OF COCKS.

1,140,938.

Specification of Letters Patent. Patented May 25, 1915.

Application filed February 20, 1913. Serial No. 749,679.

To all whom it may concern:

Be it known that I, RENÉ BABLON, manufacturer, citizen of the French Republic, residing at 14 Rue de Bagnole, Les Lilas, 5 Department of the Seine, France, have invented certain new and useful Improvements in the Construction of Cocks, of which the following is a specification.

In the known types of cocks, the different 10 members are kept in place by means of screws, nuts, dowels, etc. These securing members are apt to work loose, the result being, at least, a leakage or even the loss of one of the principal members. In certain 15 cases, serious accidents have resulted. Furthermore the dismounting and assembling of these cocks require a rather long period of time and the use of tools which are not always accessible.

20 The cock forming the object of the present invention is for the purpose of preventing the possibility of the members working loose accidentally and getting lost. Moreover it insures automatic compensation of 25 the play which tends to arise in consequence of the wear of the spigot and the body of the cock, all leakage being thereby prevented. However, the dismounting and assembling of these members can be effected manually 30 in a very short period of time and without the necessity of using any kind of tool.

The accompanying drawings represent, by way of example, three variants of the device 35 arranged in accordance with the principle of the invention.

Figure 1 is a lateral elevation of a cock. Fig. 2 represents the same cock in longitudinal section. Fig. 3 is a plan. Fig. 4 is a 40 plan view at the moment of dismounting. Fig. 5 shows a vertical section through the axis of the spigot. Fig. 6 is a longitudinal section through a variant of the device. Fig. 7 is a plan of said variant. Fig. 8 represents partly in elevation and partly in section, another variant more particularly intended to be operated by means of cords or draw-chains. Fig. 9 is a plan of this variant. Fig. 10 is a view of the spigot and 45 body of the cock from below. Fig. 1 gives a view of the cock as a whole, consisting essentially of three members; a body 1, a spigot 2 fitting into said body and a handle 3, of any shape whatsoever, intended to turn the spigot into the opening and closing positions.

The body 1 is provided with a portion 4,

either cast in one piece with or screwed on to it, and exhibiting a circular groove 18 and a corresponding projection 8 interrupted by 60 a gap 9—10 as shown in Fig. 4. Two recesses 5 are provided in the upper flange of the groove 18. The spigot is provided with a groove 17 enabling it to be embraced easily by the portion marked 2 in Fig. 1. 65

The operating handle 3 (Fig. 2) is provided with two lugs 6 of such dimensions that they can enter the recesses 5 and move inside the circular groove 18. This handle is able to fit, without any play, into a slot 16 70 in the spigot 2, (Fig. 5). This latter is provided with a projecting pin 11 and a passage 14 housing a spring 15. The passage 14 is bounded at its upper portion by the slot 16. The aggregate thus constituted 75 operates in the following manner: The spigot 2 provided with the spring 15 being inserted into the body 1 so that the slot 16 faces the recesses 5, (Fig. 4) the handle represented by broken lines is inserted in 80 the slot 16. The lugs 6 pass through the recesses 5 and enter the circular groove 18. At this moment, the projecting pin rests on the ridge 8, (Fig. 4) and all that is needed is to turn the handle 3 toward the left in 85 order that, as a result of the movement of the spigot 2 in the same direction, the said pin may drop into the gap intended for its reception. Under the action of the spring 15, the spigot enters the body completely 90 and, henceforward, its movement of rotation will be restricted by the pin making contact against 9 or 10, respectively. The handle will therefore take up the extreme positions marked by full and broken lines in 95 Fig. 3, according as the cock is open or shut, describing the arcs *a b, c d*. This movement however will never bring the lugs 6 opposite the recesses 5. On the other hand, the spring 15 by bearing against the handle 3, 100 keeps the spigot 2 embedded in the body 1 and the pin in its gap. It is therefore impossible for the aggregate to become dismounted spontaneously and, in proportion as the spigot gets worn into the body, the 105 play is automatically corrected by the action of the spring 15. Finally, this spring being situated internally and thus protected from all shock does not get out of order. To take the cock to pieces all that is needed is to 110 draw the spigot out of the body in order to disengage the pin from its gap, then turn the handle 3 so as to bring it opposite the recesses 5, whereupon the handle and spigot

can be drawn out with ease. Owing to its direction, the movement for drawing out the spigot cannot be performed except with the definite intention of taking the cock to 5 pieces.

Figs. 6 and 7 represent a constructional variant of the cock just described. It is easy to see, from an examination of Fig. 6, that this variant is constituted by the same members as the previous cock with the sole difference that the groove 18 is arranged internally instead of on the outside. The recesses 5 are consequently arranged on the inside of the upper flange of the groove 18 and the lugs 6 of the handle point toward the outside instead of toward the inside. This variant has been drawn as a cock with a body that is open underneath, an arrangement enabling the spigot to be pushed up from below when taking the cock to pieces, and since the groove 17 is no longer needed, the length of the spigot can be reduced.

Figs. 8, 9 and 10 show another variant based, in all cases, on the same principle. 25 The spigot of the cock is formed of a trunconical core 2 provided in its upper part with a projecting ridge 19 in which are arranged two gaps 20—21, 22—23 in diametrically opposite positions, while in its lower part it is provided with two diametrically opposite sectional ridges 24 and 25 each of which occupies one fourth of the circumference (Fig. 30 10). When the spigot is in position in the body of the cock, its movements are limited by a projecting pin 11 carried by the body and against which abut the ends of the sectional ribs 24 or 25. The handle consists of 35 a cylindrical metal rod 26 the ends of which are of smaller diameter than the central portion 27. The upper part of the body is pierced by two diametrically opposite grooves, one of which is visible at 28 in Fig. 40 8. The width of these grooves is equal to the diameter of the ends 26 of the handle rod. 45 At one of their diametrically opposite ends, each of them exhibits a circular enlargement 29 the diameter of which corresponds to that of the central enlarged portion 27 of the handle rod. A spring 15 is housed in a 50 cavity bored along the axis of the spigot. This cock is assembled in the following manner: The spigot is inserted into the body so that the gaps 20—21 and 22—23 are respectively opposite the enlarged orifices 29. The 55 pin 11 then bears on one of the sectional ribs 24 or 25, the spring is placed in its housing and the rod 26, 27 is inserted in one of the orifices 29, passed into the gaps 20—21 and 22—23 and finally pushed through the orifice 29 diametrically opposite to that through which it was inserted. During the operation, care has been taken to lower the spring 60 15 so that once the rod is in position it is

underneath said rod and bears against same (Fig. 8.) If then the spigot be turned by 65 means of the rod (which is feasible because the rod fits in the gaps 20—21, 22—23) the pin 11 ceases to bear on one of the sectional ribs 24 or 25 and the spigot takes up its place inside the body under the action of the 70 spring 15. From this moment, it is evident that the cock can no longer be dismounted unintentionally, the movement of the spigot being restricted to 90° by the pin 11 and the projections 24 and 25 which 75 are disposed in such a manner that the rod 26 can no longer come opposite the orifices 29 when it is moved. The rod 26 is therefore held in place owing to the fact that its enlarged portion 27 cannot pass through the grooves 28. To take the cock to pieces all that is needed is to press against the bottom of the spigot to cause it to rise and release the pin 11, the rod 26 being then turned to bring it opposite the orifices 29, and drawn out.

The cocks described above present the following advantages: The maximum safety in use, owing to the elimination of any parts apt to cause leakage; immediate dismounting without the aid of a tool, thus facilitating the rapid greasing and cleaning; automatic compensation of wear on the spigot and body, preventing any leakage between these two members.

This system of cock can be applied to all purposes that can be suggested in practice, and the members described may be modified in any necessary way, or even replaced by similar members employed in the same way, 100 without departing from the principle of the invention.

What I claim is:

A cock comprising in combination a body portion formed with a circular groove, with 105 the upper flange thereof presenting two diametrically opposite notches, and an upper arcular ridge; a slotted spigot located in said body portion and carrying a pin primarily engaging said ridge; a handle adapted to 110 seat in the slot in said spigot and formed with lugs adapted to pass through said slots prior to their engagement with said circular groove; and a spring located between said spigot and said handle and adapted upon a 115 partial rotation of said handle and spigot to force the spigot into a position in which said pin is located between the ends of said arcular ridge.

In testimony whereof I affix my signature 120 in presence of two witnesses.

RENÉ BABLON.
